CASCADE TYPE MERCHANDISING RACK

John F. Gray, N. Old Barrington Road,
Barrington, Ill. 60010

Filed Aug. 12, 1971, Ser. No. 171,406

Term of patent 14 years

Int. Cl. D6—04

U.S. Cl. D6—190

FIG. 1

FIG. 2

FIG. 3

FIG. 1 is a left side perspective view of a cascade type merchandising rack embodying my new design;

FIG. 2 is a front perspective view;

FIG. 3 is a right side perspective view; and

FIG. 4 is a rear perspective view.

I claim:

The ornamental design for a cascade type merchandising rack, substantially as shown.
